SHELF EDGING

Edward Karfiol, Great Neck, N. Y.

Application September 15, 1937, Serial No. 163,899

15 Claims. (Cl. 41—10)

This invention relates to shelf edging and, while adapted for general application, is particularly useful in connection with shelf edgings made in whole or in part of paper.

5 The object of the invention is to provide a shelf edging of novel and pleasing appearance which may be economically manufactured and will hold its shape well when placed on a shelf.

10 The edging of this invention has a bound or finished upper edge, formed by folding a projecting marginal extension of one facial ply over the upper edges of a plurality of other plies and securing it in face-abutting relation with the other facial ply, preferably by an adhesive. The

15 folded over marginal extension of the one facial ply may be substantially flush with the exposed face of the latter ply or otherwise, and the plies may be embossed or provided with perforated and printed ornamentation, or both, to produce highly ornamental and pleasing designs.

20

It is of importance in the present invention that, when the plies are assembled, one of the facial plies is offset to provide a recess into which the marginal extension of the other facial 25 ply is received. This offset has a pronounced strengthening effect upon the upper margin of the edging and tends to hold the upper edge straight against the front edge of a shelf and preclude buckling. I am thus able, by the present invention, to produce a highly efficient shelf edging with marked economies, while the resulting structure possesses the mechanical requirements for a nice tailored fit when placed on the shelf.

35 The structure is such, moreover, as to permit of an almost unlimited choice of designs without appreciably increasing the cost of manufacture.

40 Features of the invention, other than those adverted to, will be apparent from the herein-after detailed description and claims, when read in conjunction with the accompanying drawing.

The accompanying drawing illustrates different practical embodiments of the invention, but the constructions therein shown are to be understood as illustrative, only, and not as defining the limits of the invention.

Figure 1 is a front elevation of a three ply
edging embodying the present invention.

Figure 2 is a section perspective taken on the line 2—2 of Figure 1.

Figure 3 shows short lengths of the several plies and illustrating the manner in which they are formed prior to assembling.

Figure 4 is a view similar to Figure 2, but showing a modified form of the invention.

Figure 5 shows a further modified form of the invention.

invention. While the edging of this invention may embody three or more plies of material, I have chosen three plies as thoroughly satisfactory in the production of an economical and thoroughly efficient structure. In the showing of Figures 1-3, 1 designates the back ply, 2 the intermediate ply and 3 the front ply. The back ply is adapted to be folded over the upper edges of the other two plies along a fold line indicated at 4. As shown in Figure 3, the body of the back ply 1 projects downwardly from the fold line 4 for the desired overall width of the edging and it is provided at its top with a marginal extension 5 which projects a sufficient distance above the fold line to provide an adequate flap for folding over the upper edges of the other plies. The free edge of this extension may be made straight or may be of any suitable configuration. For the purpose of illustration, it is shown as serrated at 6. 5 10 15 20

The intermediate ply is adapted to be secured in face abutting relation to the back ply. It is shown as extending downwardly to the lower edge of the back ply, although it may extend for a greater or lesser distance in this direction. It, however, terminates at its upper edge short of the fold line 4 a distance about the same as the distance which the extension 5 projects beyond the fold line 4, so that, when the plies 1 and 2 are adhesively secured together in face abutting relation, as indicated by the adhesive 7 in Figure 2, the extension 5 will project beyond the ply 2 a distance about twice the distance of the upper edge 8 of the intermediate ply 2 from such fold line. The front ply 3 is of a width to extend from the fold line downwardly to an elevation preferably short of the lower edges of the other plies 1 and 2, as clearly shown in Figure 3. 25 30 35 40

In the structure thus far described, the several plies are assembled at the elevation shown in Figure 3. The ply 2 is first laid on the ply 1 at the relative elevation shown, and the ply 3 is then laid on the ply 2. The plies 1 and 2 are facially secured together by gluing them throughout or at spaced apart points, and the ply 3 may be similarly secured in place. However, I preferably leave the ply 3 loose below the upper edge 8 of the intermediate ply, while the upper margin of the ply 3 is glued to the body of the back ply 1 below the fold line thereof. In some cases the front ply 3 is secured along its upper

portion to the front face of the intermediate 5
ply 2. After the parts have been secured together, as stated, the extension 5 of the back
ply is folded over the upper edge of the front 10
ply and secured in face abutting relation to the front
ply. As this operation is carried out pressure
may, if desired, be applied to the extension to
flatten the extension 5 into flush relation with
the front face 10 of the front 15
ply, although this pressure may be dispensed with so as to leave a rolled or round upper edge, as shown in Figure 4, hereinafter described. The edges of the several plies may be scalloped, serrated or otherwise 20
configured as may be desired to carry out a predetermined design and one or more of these plies may be printed or perforated or both. As shown in Figures 1-3 of the drawing the front 25
ply 3 is both perforated and printed. The perforations are indicated at 11 and form part of the predetermined design.

If desired, I may apply relatively great pressure to the parts as they are assembled, for the purpose of embossing said parts while gluing them together. In this way I am able to force the extension 5 to offset the front 30
ply to give the flush relation described and produce the offset 12 which serves in effect as a strengthening rib. At the same time the intermediate 35
ply may be compressed to an extent as to cause said intermediate 40
ply to be slightly bulged or embossed as indicated at 13 by virtue of the presence of the opening of the perforations 11. This is accomplished by pressing the front 45
ply into the intermediate 45
ply so as to form, in effect, a depression therein bordered at its lower edge by a shoulder 14 at the lower edge of the front 50
ply. At the same time an embossed lower edge 15 may be formed in both the intermediate and back plies 2 and 1. When the parts are secured together 55
in this way a relatively thin edging is produced but one of marked strength and appreciable longitudinal stiffness, due to the reinforcing of the upper edge by the folded over extension 5 and by the presence of the offset 12. Also, when the three 60
ply structure at the upper margin of the edging is glued together as stated, an unusually stiff edge is provided which will hug the shelf closely and allow the edging to hang with a smooth tailored appearance. I wish it understood, however, that this pressure embossing is optional and that I may make the edging without it if desired.

The structure shown in Figure 4 embodies a modification of the invention as hereinbefore described. Here the offset portion 16 of the front 65
facial 17 is made to terminate in distance short of the fold line 4, so that, when the marginal extension 18 of the back 70
ply 19 is folded over, a part of this extension will come into face 75
abutting relation with the back 70
ply, while the rest of the extension will come into face abutting relation with the upper margin of the front 75
ply 17. This arrangement produces two offsets or beads 20 and 21 which impart a double reinforce 80
to the upper portion of the edging. The intermediate 85
ply 22 terminates at the offset 21, as in the preceding figures.

Figure 4 shows the structure as made without the application of appreciable pressures and 90
with the parts glued together to hold them in assembled relation with the upper edge of the edging in the form of a relatively loose rolled or round edge and with the parts glued together as indicated by the solid black lines 23 in this figure. It will of course be understood that the

structure of Figures 1-3 may have the same kind of a round fold at the fold line.

It will be noted that when the intermediate 5
ply is cut low and in spaced relation to the fold 10
line, this results in economies in stock from which this ply is made. Also, this narrowing of the intermediate 15
ply in Figures 1-4 or of both the intermediate and front 20
ply as in Figure 4, serves to produce the offsets or strengthening beads to impart rigidity in the upper margin of the edging 25
to hold the edging in close-fitting relation to the front edge of the shelf.

In the forms of the invention which I have chosen to show, the marginal extension is shown as formed on the back 30
ply and is folded over the upper edge of the front 35
ply to be secured to the front face of the latter. This arrangement, however, may be reversed so that the front 40
ply will have the extension folded over and secured to the back face of the back 45
ply. Such a reversed arrangement is shown in Figure 5 wherein the front 50
ply is indicated at 24 and is provided with an extension 25 folded over the upper edge of the back 55
ply 26, while an intermediate 27
terminates at its upper edge short of the free 60
edge of the extension 25. For these reasons and others which will be apparent from the foregoing description, the present invention is not restricted to the detailed showings of the drawing.

Having thus fully described the invention, what I claim as new and desire to secure by Letters Patent is:

1. A shelf edging comprising a back 65
ply, a front 70
ply and an intermediate 75
ply, the back 80
ply being provided at its upper edge with an extension 85
to be folded over the upper edge of the front 90
ply and secured to the front face of the front 95
ply and said intermediate 100
ply terminating at its upper edge short of the free edge of said folded extension, with said extension and the front 105
ply and the back 110
ply all being in face abutting relation above the upper edge of the intermediate 115
ply.

2. A shelf edging comprising a front 120
ply, a back 125
ply and an intermediate 130
ply, the back 135
ply being provided with an extension folded over the upper 140
edge of the front 145
ply and secured in face abutting relation to the front face of the latter 150
ply, and the intermediate 155
ply terminating at its upper edge short of the free edge of the extension.

3. A shelf edging comprising a back 160
ply, a front 165
ply and an intermediate 170
ply, the back 175
ply having an extension folded over the upper edge 180
of the front 185
ply into face abutting relation with the front face of the front 190
ply with the upper edge of the intermediate 195
ply below the free edge 200
of the extension, and means for securing said plies together and the extension in folded condition.

4. A shelf edging comprising a back 205
ply, a front 210
ply and an intermediate 215
ply, the back 220
ply having an extension folded over the upper edge 225
of the front 230
ply into face abutting relation with the front face of the front 235
ply with the upper edge of the intermediate 240
ply below the free edge 245
of the extension, said intermediate 250
ply being adhesively secured to the front face of the back 255
ply and that portion of the front 260
ply above the upper edge of the intermediate 265
ply being also adhesively secured to the front face of the back 270
ply and the extension being adhesively secured to the 275
underlying front face of the front 280
ply.

5. A shelf edging comprising a back 285
ply provided with an extension, a front 290
ply the upper 295
marginal portion of which is offset in a rearward 300
direction and adhesively secured to the back 305
ply, 75

- with the extension folded over the upper edge of the front ply and adhesively secured to the front face of the offset portion of the front ply, and an intermediate ply between the front and back plies and extending downwardly from the offset of the front ply.

6. A shelf edging comprising a back ply provided with an extension, a front ply the upper marginal portion of which is offset in a rearward direction and adhesively secured to the back ply, with the extension folded over the upper edge of the front ply and adhesively secured to the front face of the offset portion of the front ply, and an intermediate ply between the front and back plies and extending downwardly from the offset of the front ply and adhesively secured at its back face to the front face of the back ply.

7. A shelf edging comprising two facial plies, one of which is provided with an extension folded over the upper edge of the other and secured to the remote face of the latter, said latter ply being offset below the free edge of the extension to provide therebetween space for at least one intermediate ply, and at least one intermediate ply secured in the space thus provided.

8. A shelf edging comprising two facial plies, one of which is provided with an extension folded over the upper edge of the other and secured partly to the facial ply on which it is formed and partly to the remote face of the other facial ply, said latter facial ply being offset below the free edge of the extension to provide therebetween space for at least one intermediate ply and at least one intermediate ply secured in the space thus provided.

9. A shelf edging comprising a back ply provided with an extension, a front ply, the upper marginal portion of which is offset in a rearward direction and adhesively secured to the back ply below the upper edge of the latter, with a portion of said extension folded into face abutting relation with the front face of the back ply and secured thereto and the remaining portion of the extension offset to overlie the front face of the front ply and secured thereto, and an intermediate ply between the front and back plies and extending downwardly from the offset of the front ply and secured at its back face to the front face of the back ply.

10. A shelf edging comprising a back ply having an extension, a front ply, and an intermediate ply, the front ply being offset in a rearward direction over the upper edge of the intermediate ply with the offset secured to the front face of the back ply, and the extension of the back ply being secured for a portion of its width in face abutting relation to the back ply and offset forwardly with said offset portion secured to the front face of the front ply.

11. A shelf edging comprising a back ply, a front ply and an intermediate ply, the back ply having an extension folded over the upper edge of the front ply into face abutting relation with the front face of the latter ply, and with the upper edge of the intermediate ply below the free edge of said extension, both the front ply and the extension being offset to provide reinforcing beads extending longitudinally of the edging and positioned in spaced relation to the upper edge thereof.

12. A shelf edging comprising a back ply, a front ply and an intermediate ply, the back ply being provided at its upper edge with an extension to be folded over the upper edge of the front ply and secured to the front face of the latter ply and said intermediate ply terminating at its upper edge short of the free edge of said folded extension, said extension, the front ply and the back ply being in face abutting relation above the upper edge of the intermediate ply, and the exposed front faces of the extension and the front ply being substantially flush with one another.

13. A shelf edging comprising a back ply provided with an extension, a front ply the upper marginal portion of which is offset in a rearward direction and adhesively secured to the back ply, with the extension folded over the upper edge of the front ply and adhesively secured to the front face of the offset portion of the front ply, and an intermediate ply between the front and back plies and extending downwardly from the offset of the front ply and that portion of the front ply which overlies the intermediate ply being depressed into the intermediate ply.

14. A shelf edging comprising a back ply provided with an extension, a front ply the upper marginal portion of which is offset in a rearward direction and adhesively secured to the back ply, with the extension folded over the upper edge of the front ply and adhesively secured to the front face of the offset portion of the front ply, and an intermediate ply between the front and back plies and extending downwardly from the offset of the front ply and that portion of the front ply which overlies the intermediate ply being depressed into the intermediate ply, but free from facial attachment thereto.

15. A shelf edging comprising a front ply, a back ply and an intermediate ply, the front ply being provided with an extension folded over the upper edge of the back ply and secured in face abutting relation to the back face of the latter ply, and the intermediate ply terminating at its upper edge short of the free edge of the extension.

EDWARD KARFIOL.
